(57) **CLAIM**

We claim the ornamental design for a clipper, as shown and described.

DESCRIPTION

FIG. 1 is a perspective view showing a clipper in accordance with our new design;

FIG. 2 is a top plan view thereof;

FIG. 3 is a right side elevational view thereof;

FIG. 4 is a front elevational view thereof;

FIG. 5 is a left side elevational view thereof;

FIG. 6 is a rear elevational view thereof; and,

FIG. 7 is a bottom plan view thereof.

The broken lines illustrate portions of the clipper and form no part of the claimed design.
